[57] CLAIM

The ornamental design for a “article pouch”, as shown and described.

DESCRIPTION

FIG. 1 is a front elevational view of an article pouch showing my new design, with the flap shown in a closed position;

FIG. 2 is a right side elevational view, with the left side elevational view being a mirror image thereof;

FIG. 3 is a rear elevational view;

FIG. 4 is a front elevational view, with the flap shown in an open position;

FIG. 5 is a right side elevational view, with the left side elevational view being a mirror image thereof;

FIG. 6 is a top front elevational view;

FIG. 7 is a top rear elevational view;

FIG. 8 is a bottom plan view thereof; and,

FIG. 9 is a front elevational view, with the flap shown in a closed position and in a position of use. The broken line showing of a person in FIG. 9 is for illustrative purposes only and forms no part of the claimed design.
